ARABIC ALPHABET

Nasri N. Khattar, New York, N. Y.

Application June 21, 1947, Serial No. 139,868

Term of patent 14 years

(Cl. D64—12)

To all whom it may concern:

Be it known that I, Nasri N. Khattar, a citizen of the Republic of Lebanon and a resident of New York, in the county of New York, State of New York, have invented a new, original, and ornamental Design for an Arabic Alphabet, of which the following is a specification, reference being had to the accompanying drawing, forming a part thereof.

The drawing illustrates face views of an Arabic alphabet, showing my new design.

I claim:

The ornamental design for an Arabic alphabet, substantially as shown.

NASRI N. KHATTAR.
